UNITED STATES PATENT OFFICE.

GEORGE HILLARD BENJAMIN, OF NEW YORK, N. Y.

BLOCKING ATTACHMENT FOR STRIP-MILLS.

1,277,029.

Specification of Letters Patent. Patented Aug. 27, 1918.

Application filed February 15, 1915. Serial No. 8,405.

To all whom it may concern:

Be it known that I, GEORGE HILLARD BENJAMIN, a citizen of the Untied States, residing at New York city, in the county and State of New York, have invented a certain new and Improved Blocking Attachment for Strip-Mills, of which the following is a specification.

My invention consists in an automatic 10 blocking attachment, adapted to be used in connection with the rolls of a strip mill.

The objects of my invention are:

First: To do away with the use of removable blocks by substituting a fixed, collapsible block.

Second: To provide means for automatically guiding a strip, after passing the rolls of a strip mill, on to and around the block.

Third: To provide means whereby a constant tension shall be exerted on the strip as it passes from the strip mill to the block.

Fourth: To provide means for automatically separating the guiding means from the block, and allow automatic discharge of the 25 coiled strip from the block.

Automatic blocking attachments for strip mills have hertofore been used, but so far as I am aware, have always been provided with removable blocks, and further, no 30 means have been provided for exerting a constant tension upon the strip as it passes from the strip mill to the block.

In my improved device, the removable block is done away with, and there is substituted a collapsible block, which receives the strip from the strip mill, and when the block is full, it is collapsed to automatically discharge the strip from the block.

In blocking attachments as usually made, 40 the shaft which carries the block is run at a given speed, with the result, that as the strip is wound upon the block, the diameter of the coiled strip is increased, which, owing to increase in peripheral speed, increases the 45 tension exerted upon the strip as the strip rolls are also run at a given speed, and therefore feed the strip at a uniform rate.

In my improved device, the speed of the shaft which carries the block, is decreased 50 by appropriate means in direct proportion as the diameter of the coiled strip increases, and thus provision is made for a constant tension upon the strip. One of the advantages of my improved construction, is 55 that the blocking attachment may be used both for coiling and blocking, which in the

present practice, is usually performed by two separate devices.

The accompanying drawings will serve to illustrate my invention, in which Figure 1 is 60 a plan view and partial horizontal section taken on the line I—I of Fig. 3, this figure also showing in plan, the relation of the blocking attachment to the strip rolls. Fig. 2 is an elevation showing a modification of 65 the mechanism employed to drive and regulate the speed of the block. Fig. 3 is a front elevation. Fig. 4 is a transverse section taken on the line IV—IV of Fig. 3 of the blocking attachment and also a transverse 70 section taken through the strip rolls. Fig. 5 is a transverse section taken on the same line as Fig. 4, and showing the controlling means for the device which guides the strip around the block, in a different position. 75 Fig. 6 is a longitudinal section taken on the line VI—VI of Fig. 7 and shows the parts in the position at which the coiled strip is discharged from the blocking attachment. Fig. 7 is a transverse section taken substantially 80 on the line IV—IV of Fig. 3, and showing the controlling means for the device which guides the strip around the block, in the discharging position.

Referring to the drawings: 1 and 2 represent the rolls of a strip mill, and 3—3 the side frames in which the rolls are mounted in the usual manner. Situated in front of the rolls 1—2 are two guides, 4 and 5. The guide 4 is fixed in position, and the guide 5, 90 which is located under it, is pivoted at 6. Situated under the forward part of this guide is a spring 7, which tends to press the guide upward. The object of pivoting the guide 5 is to permit the forward end of the 95 guide to move downward, as the strip indicated at 8, is wound upon the block 9. The positions of the guide 5, when the strip is first fed to the block and as wound on the block, are indicated respectively in Figs. 4 100 and 5.

The construction of the rolls 1—2, frame 3—3, guides 4—5, is substantially the same as that which has heretofore been used, and forms no part of my invention, except in so 105 far as the guides coöperate with the blocking attachment. The blocking attachment is situated in front of the strip rolls 1—2, and consists of a frame 10, the upper part of which is provided with bearings 11—12 for 110 a tubular shaft 13. The rear end of this shaft is connected to a source of power, as

will hereinafter be described, by reason of which the shaft 13 is driven. The front end of this shaft is connected to a block 9. The block 9 consists essentially of a wheel 14, 5 around the outer circumference of which is pivoted at 15, a series of arms 16. The arms 16 are so shaped that in one position (*i. e.*, in the blocking position shown in Fig. 1) the free ends of the arms will collectively form 10 a circular block to receive the strip 8, and in another position (*i. e.*, the discharging position shown in Fig. 6) the free ends of the arms will form a cone-shaped body, from which the wound strip 8 will be 15 discharged by gravity. Motion is imparted to the arms 16, to take the first or second positions, as described, through the instrumentality of a rod 17, which is located within the tubular shaft 13. On the outer end of 20 this rod is a disk 18, which is located within the space inclosed by the free ends of the arms 16. Suitably connected to the rear end of the rod 17, so as not to interfere with rotation of the shaft 13, is a lever 19, the object of which lever is to reciprocate the rod 25 17, so that when the rod 17 is moved forward, the disk 18 thereon, by taking against shoulders 20 formed on the arms 16 of the block, will cause the arms to be moved from 30 the position shown in Fig. 6 to the position shown in Fig. 1. During the last part of the forward movement of disk 18, the periphery thereof will be bearing against surfaces 21 formed on the arms 16, and will 35 thereby serve to support the arms, while the strip 8 is being wound thereon. When the shaft 17 and disk 18 are moved backward, the disk 18, by taking against shoulders 22 formed on the arms 16, will cause the arms 40 to be moved from the position shown in Fig. 1 to the position shown in Fig. 6. To impart motion to the lever 19, and thereby reciprocate the rod 17, a grooved cam 23 is 45 provided. On an arm 24 forming part of the mechanism controlling the rod 17, is a pin 25, riding in the cam groove 26; the cam 23 is loosely mounted upon a shaft 27, which shaft receives its motion from the source of power which will hereinafter be 50 described.

Mounted on the shaft 27 in front of the cam, is a clutch device 28. This clutch device is actuated by an arm 29 which is secured to a rock-shaft 30 having a lever 31 55 secured thereto. On one end of lever 31 is a handle 32, and the other end of the lever is connected by a link 33 to an arm 34 on the end of the shaft 35, which has its bearings in the frame 10 at 36. On the end of the shaft 35 is secured a trigger 37. A spring 38 normally holds the lever 31 in the position shown in Fig. 3.

It will be understood that by moving the lever 31 in one direction, the portion of the 60 clutch on the shaft 27 will be brought into

engagement with the portion of the clutch on the cam 23, and thus the cam will be rotated by the shaft. When the cam is rotated in one direction, the pin 25 moves in the cam groove 26, with the effect that the 70 rod 17 and the arms 16 are moved from the position shown in Fig. 1 to the position shown in Fig. 6; and further, that if the clutch 28 is thrown out when the parts are in the position shown in Fig. 6, by movement 75 of the lever 31 in the opposite direction by means of spring 38, they will remain in that position until the clutch is again thrown to effect engagement of its parts, when the rotation of the cam 23 will cause the pin 25 to 80 move in the other half of the cam groove 26, and cause a movement of the parts from the position shown in Fig. 6 to the position shown in Fig. 1, when, if the clutch is again thrown out, the parts will remain in the position shown in Fig. 1.

The operation of the trigger 37, which is actuated simultaneously with the clutch, will hereinafter be described in connection with the parts with which it co-operates.

The mechanism used for guiding the metal strip around the block is as follows: Projecting horizontally from the top of frame 10 of the machine, is an arm 39. Mounted on this arm is a roller 40 which is 90 free to rotate on a shaft 41 carrying links 42. These links at their lower ends are pivotally connected with one of a series of shafts 43 carrying a series of rollers 44 which are connected together by links 45. 100 Eleven of such shafts and rollers are shown. Pivoted to the shaft on which the first roller of the series is journaled, is a shaped guide plate 46 carrying a shaft 47 on which is journaled a large roller 48. Connected to 105 the shaft on which the last roller of the series is journaled is a shaped guide plate 49, carrying two rollers 50-51. Connected to the guide plate 46 are links 52. These links at their lower ends are pivotally connected to levers 53, secured to one end of a shaft 54 having its bearings 55 in frame 10. Connected also to the shaft 54 is a lever 56. The levers 53 and 56 are substantially at right angles; and connected to the lower 115 end of the lever 56 is a link 57, pivotally connected at 58 to a shaped arm 59 which is secured to one end of a rock-shaft 60. Secured to the other end of rock-shaft 60 is another shaped arm 59 having a handle 61 120 secured thereto (see Fig. 3).

Forming part of the guide plate 49 is a frame 62, which frame is adapted to coact, when the parts are in the position shown in Figs. 4 and 5, with the trigger 37. On the 125 end of the frame 62 is a cross-bar 63, which bar is adapted to move in a shaped cam slot 64, formed in the main frame 10. The positions of the rollers, arms and links, as described, when the strip is fed to the block, 130

is wound on the block, and is being discharged from the block, are respectively shown in Figs. 4, 5 and 6.

Situated on the rear end of the shaft 54 is a lever 65 connected by means of links 66 with a rack bar 67 in engagement with a pinion 68 mounted on a shaft 69. Mounted also on this shaft is a second pinion 70 in engagement with a rack bar 71. This rack bar is provided with horizontally extending pins 72, disposed on opposite sides of a belt 73 which passes over the cone pulleys 74-75. Cone pulley 74 is secured to a shaft 76 forming part of the hollow shaft 13, and having its bearings in the frame 10, and pulley 75 is secured to shaft 27 which also has its bearings in the frame 10. Secured to the shaft 27, is a driving pulley 77 (Figs. 1 and 3) which may be connected with any suitable source of power, or alternatively a train of gears 78-79 may be employed, connected to a suitable variable speed motor 80, connected to any source of electrical energy, as shown in Fig. 2.

In Figs. 1, 3 and 6, means are provided for driving the blocker at a variable speed in accordance with the number of layers of strip wound on the block, by shifting a belt over the cone pulleys, in a manner well understood, and in Fig. 2 through the instrumentality of a variable speed motor which may be of any construction. I have shown two methods of driving, as I wish it understood that I may use either method, as 35 may be most convenient.

In the construction shown in Figs. 1, 3 and 6, the belt shifting is effected by the movement of the shaft 54, which movement is imparted through the levers and links 40 connected to the train of rollers 44 and 50-51, and the horizontally moving rack bar 65, pinions 68 and 70, and rack bar 71. The positions occupied by the lever 65 are illustrated in Figs. 4 and 5 by dotted lines.

By reference to Figs. 4 and 5 it will be seen that as the strip 8 is wound upon the block, the rollers 50-51 are held in position under the block by the frame 62 in engagement with the trigger 37, and that when the 45 trigger 37 is released by reason of movement imparted to the lever 31, which acts to throw the parts of the clutch 28 into engagement with the cam 23, the frame 62 will be released, causing it and the series of 50 rollers 44 and 50-51 to take the position shown in Fig. 7, or in other words, are separated from the block, thereby permitting the coiled strip to be discharged from the block.

To restore the series of rollers 44 and 50-51 to their original position as shown in Fig. 4, the handle 61 is used. When this handle is used, the shaped arms 59 are moved forward and upward, and by taking against 55 the ends of shafts on which rollers 50-51

are journaled, carry the frame 62 with them, thereby causing the cross-bar 63 of frame 62 to make a downward movement in the cam slot 64, until the end of the frame passes and is engaged by the trigger 37. It will 70 thus be seen that the series of rollers 44 and 50-51 have a double function, *i. e.*, to guide the strip 8 around the block, and as the diameter of the coil or number of layers of the coil is increased, actuate the levers to move 75 the belt shifting device to a position where the speed of rotation of shaft 13 will be decreased in proportion to the increased diameter, thereby maintaining a constant pull or torque upon the strip as it is wound upon 80 the block. Manifestly, if the method of driving shown in Fig. 2 is employed, the rear portion of the shaft 54, lever 65 and belt shifting device, may be dispensed with, as the regulation of the motor is inherent in 85 the motor and does not require the action of exterior means to effect a change of speed. It will be obvious, that instead of using a variable speed motor, any motor may be employed, and the device disclosed as a belt 90 shifting device used to vary resistance, or otherwise, to change the speed of the motor.

I wish it understood that I do not limit myself to the specific features of the mechanism of the collapsible block, strip guiding 95 means, speed governing means, etc., as these may be considerably varied without departing from my invention. I make this statement, as I believe I am the first to describe the employment of a collapsible block, a device 100 for guiding the strip around the block, *i. e.*, a device which will not only guide the strip but indicate the thickness of the wound coils upon the block and thus determine the speed of rotation of the block, and which 105 may also be separated from the block, but permit automatic discharge of the wound strip from the block; and the means disclosed whereby the speed of rotation of the block is varied in accordance with the thickness 110 of the strip, whereby a constant speed is given to the block and a constant torque exerted upon the strip as it is wound on the block.

Connected to the shaft 27 is a gear 81 in 115 mesh with a gear 82 mounted on shaft 83, having its bearings in frame 10. Connected to the shaft 83 is a bevel gear 84 in mesh with a large bevel gear 85 on a shaft 86. To shaft 86 is secured a drum 87 over which 120 passes a moving belt 88, which may be formed of wire or other material, and which acts to receive the wound strip or coil 8 when discharged from the machine, and to convey it from the machine. The last described 125 conveying mechanism forms no part of the machine and is described merely to illustrate means for conveying the coil from the machine after it leaves the block.

The operation of the blocking attachment 130

is as follows: The strip 8 is passed through the rolls 1—2 and then through the guides 4—5 to the block 9. When the end of the strip reaches the block, it is caught between the rollers 50—51 and the block, and moves with and on to the block. When the end of the strip reaches the roller 48 and the shaped plate 46, it is guided into position between the surface of the block and the advancing strip. As the strip is wound upon the block, its diameter is increased, and as the peripheral speed of the block with the coil thereon will be greater than the peripheral speed of the block without the coil, it will be understood that unless some means were provided for decreasing the peripheral speed, the torque exerted by the block upon the strip would be greater than needed for compact winding of the strip as it is regularly fed from the strip rolls 1—2.

As the diameter of the strip rolled upon the block increases, the rollers 44 and 50—51 are pressed outward from the block, while still maintaining their general position as regards the block. It will be seen on reference to Fig. 4 that the series of rollers are supported by a roller 40 and links 42, which are movable along the horizontal arm 39 of the frame 10. The links 42 serve to support the series of rollers 44, and as the diameter of the coil is increased, the links change their position, from that shown in Fig. 4 to that shown in Fig. 5. At the same time, shaped plate 46 is lifted from the position shown in Fig. 4 to the position shown in Fig. 5, and carries with it the links 52 which make traction upon the levers 53, thereby moving shaft 54, lever 56, link 57, and arms 59; the change in position of these parts being respectively shown in Figs. 4 and 5. At the same time the movement of the shaft 54, progressively actuates the lever 65, and through it the rack bar 66, pinions 68 and 70, and rack bar 71, thus moving the power belt 73 along the cone pulleys 74—75, which reduces the speed of rotation of the shaft 18.

When the strip has been fully wound upon the block 9, the operator actuates the lever 31 through the handle 32, the handle being moved upward. The movement of the lever causes the two parts of the clutch 28 to engage, and thus establishes connection between the shaft 27 and the cam 28. The cam 28 will then be rotated, and the cam groove 26 will move the pin 21. This motion is transmitted through suitable mechanism (consisting of a lever and ring connection, such as is commonly used) to rod 17, thereby moving the rod from the position shown in Fig. 1 to the position shown in Fig. 6. At the same time, the movement of the lever 31, transmitted through the link 33 and arm 34, gives motion to shaft 35 and trigger 37 and releases

frame 62. The cross-bar 63 of frame 62 then moves upward in the shaped cam slot 64 from the position shown in Fig. 4 to the position shown in Fig. 7, which allows the rollers 50—51 and three of the series of rollers 44 to assume a vertical position relative to the block 9, or in other words, clears the block and thus permits the discharge from the block of the coiled strip 8 by gravity, as illustrated in Figs. 6 and 7. As the coiled strip falls, it is received upon the moving belt 88, which carries it from the machine.

When the coil has left the machine, the operator moves the handle 32 downward to bring the parts of the block to the position shown in Fig. 1, and also moves the handle 31 to move the arms 59 from the position shown in Figs. 5 and 7 into the position shown in Fig. 4. As these arms are moved upward, the link 57, levers 53 and 56, shaft 54, lever 65 and pinions of the belt shifter, are actuated to shift the belt from the position shown in Fig. 6 to the position shown in Fig. 1. At the same time, the frame 62 moves downward. This is due to the fact that the arms 59 take against the ends of shaft on which rollers 50—51 are journaled, which causes the cross-bar 63 of the frame 62 to move downward in the cam slot 64 and into engagement with the trigger 37.

It will be seen from the above description, that the arms 16 of the block 9 are under the control of the operator, and can be moved from the position shown in Fig. 1 to the position shown in Fig. 6, and vice versa, through the action of the clutch 28; and further, that the position of the guiding rolls follows the movement of the clutch, except in so far as they are hand operated to move them from the discharging position to the coiling position.

Having thus described my invention, I claim:

1. In a blocking attachment for strip mills, the combination of a revolving block, a single series of connected rollers arranged around the block, means permitting the rollers to change their position as regards the block as the strip is wound on the block, and means for removing the rollers from around the block to allow the passage of the wound strip from the block.

2. In a blocking attachment for strip mills, the combination of a revolving collapsible block, a single series of connected rollers arranged around the block, means permitting the rollers to change their position as regards the block as the strip is wound on the block, and means for removing the rollers from around the block to allow the passage of the wound strip from the block.

3. In a blocking attachment for strip mills, the combination of a revolving block,

- a series of rollers disposed around the block, a series of pivoted links acting to connect and support the rollers, means whereby the rollers may change their position as regards 5 the block as the strip is wound on the block, and means for removing the roller out of relation to the block to allow the discharge of the wound strip from the block.
4. In a blocking attachment for strip 10 mills, the combination of a block formed of a series of pivoted arms, means for directing and guiding a strip around the block, together with means for alternately altering the position of the pivoted arms to permit 15 the strip to be wound on the block, and the coiled strip to be discharged from the block.
5. In a blocking attachment for strip 20 mills, the combination of a revolving collapsible block, means for directing and guiding a strip around and upon the surface of the block, said means consisting of a series of rollers mounted in pivoted links and inclosing the major portion of the periphery of the block when in position, means for 25 separating the rollers from the block to allow discharge of the coiled strip from the block, and means for actuating said separable means.
6. In combination with the rolls of a strip 30 mill, a collapsible rotatable block situated in front of said rolls, a series of rollers, pivoted links connecting the rollers, means for separating the rollers from the block, and means for changing the configuration of the 35 surface of the block to permit discharge of the coiled strip from the block.
7. In a blocking attachment for strip mills, the combination of a revolving block, said block consisting of a ring shaped frame, 40 L-shaped arms pivoted to said frame, a reciprocating rod situated centrally of the pivoted arms, whereby the arms are caused to take defined positions; guiding means for a strip arranged around the periphery of said block and exterior to the arms, together with 45 means for reciprocating the rod to change the position of the arms and to change the position of the guiding means relative to the arms.
8. In a blocking attachment for strip 50 mills, the combination of a revolving collapsible block, means for directing and guiding a strip around the block, means for varying the speed of rotation of the block, and means interposed between the directing and 55 guiding means and the speed varying means for controlling the speed of rotation of the block.
9. In a blocking attachment for strip 60 mills, a collapsible block constructed in such a manner, that in one position the block will present a cylindrical surface upon which a strip may be wound, and in another position a V-shaped surface to permit gravitational discharge of the wound strip from the block, 65 together with means to actuate the parts of the block to alternately present the desired cylindrical and V-shaped surfaces.
10. In a blocking attachment for strip 70 mills, a revolving collapsible block, said block having parts which in one position will present a cylindrical surface of a defined diameter upon which a strip may be wound, and in another position present a surface of decreasing diameters from within 75 outward from which the wound strip may be discharged, together with means for actuating the movable parts of the block to present the surfaces as described.
- In testimony whereof, I affix my signature, 80 in the presence of two witnesses.
